B. H. SKELLY.

SIGHT FEED FOR FORCE FEED LUBRICATORS.

APPLICATION FILED MAR. 31, 1920.

1,367,630.

Patented Feb. 8, 1921.

FIG. 1.

FIG. 2.

FIG. 3.

Inventor
Bernard H. Skelly.

By Attorney

UNITED STATES PATENT OFFICE.

BERNARD H. SKELLY, OF BRIDGEPORT, CONNECTICUT.

SIGHT-FEED FOR FORCE-FEED LUBRICATORS.

1,367,630.

Specification of Letters Patent.

Patented Feb. 8, 1921.

Application filed March 31, 1920. Serial No. 370,063.

To all whom it may concern:

Be it known that I, BERNARD H. SKELLY, a citizen of the United States, residing at the city of Bridgeport, county of Fairfield,

5 State of Connecticut, have invented certain new and useful Improvements in Sight-Feeds for Force-Feed Lubricators; and I do declare the following to be a full, clear, and exact description of the invention, such 10 as will enable others skilled in the art to which it appertains to make and use the same.

This invention relates to sight feeds for force feed lubricators, but more particularly 15 has reference to devices of this description known as the "Blinker" type, in which oil appears momentarily through the sight glass and simultaneously with the oil feed impulses.

20 Sight feeds of this type have heretofore been utilized, but the plunger or closure which is operated by the oil impulses has been equipped with an oil duct extending therethrough and communicating directly 25 with the outlet which leads to the parts to be lubricated, and while this sort of feed was admirably adapted for use in connection with the heavier oils, it does not operate satisfactorily when the lighter oils are used.

30 In these devices noted, the passage through the plunger or closure chokes back the feed of the heavier oils so that the plunger will be depressed and show a discoloration beneath the sight glass before the oil has had 35 a chance to pass through the orifice in the plunger, but in the instance of the lighter oils the latter will pass through this orifice before the plunger has been depressed to any appreciable extent, and since these lighter 40 oils possess less color than the heavier oils, the film of oil between the plunger and the sight glass will be so thin that the discoloration is hardly if at all visible.

If the passage through the plunger be 45 made smaller then it will so choke the feed of the heavier oils that a back pressure will be created and there will be no satisfactory delivery of the oil to the outlet although the lighter oils would probably show discoloration through the sight glass owing to greater depression of the plunger or closure.

50 It is the object of the present improvement to provide a sight feed which shall operate equally as well in connection with 55 either the heavier oils or the lighter oils,

while at the same time added to this efficiency are simplicity and economy in construction.

Referring to the accompanying drawing:

Figure 1 is a sectional elevation illustrating the preferred embodiment of my improvement—

Fig. 2 a section at the line 2—2 of Fig. 1, and

Fig. 3 a view similar to Fig. 1 but illustrating a modified form of my improvement.

Similar numerals of reference denote like parts in the several figures of the drawing.

1 is a casing or main body portion, and 2, 3, are nipples extending from the casing and 70 adapted to be connected respectively with the oil supply and oil distributing means, these nipples having oil passages 4 and 5.

In the main body portion of the casing is 75 a recess 6 within which is a plunger or closure 7 which closely conforms to the walls of the recess but is capable of free reciprocatory movements. 8 is a coil spring confined beneath the plunger 7 and the bottom of the recess and serving to normally project the 80 plunger.

9 is a by-pass leading from the passage 4 through the top face of the casing which latter is smooth and level so as to afford a proper seat for the purposes presently to be 85 explained.

10 is a washer made of any suitable non-metallic material and seated on the top face of the casing and provided with an opening 11 with which the by-pass 9 registers. 90

12 is a sight glass seated on the washer and confined by any suitable open cap 13 that is screwed to the casing.

14 is a by-pass which leads from the outlet opening 5 in the casing and opens into 95 the wall of the recess 6 at a point below the bottom of the sight glass 12, this by-pass being normally closed by the side wall of the plunger 7.

When the oil is driven through the inlet 100 4 and by-pass 9 it will force the plunger 7 downwardly until the outer face of the plunger shall have passed the mouth of the by-pass 14, whereupon the oil will flow through said by-pass into the outlet passage 5. 105 When the pump impulses of the oil have ceased the spring 8 will return the plunger 7 to its normal position and thereby again close the by-pass 14.

It will thus be noted that the plunger 7 110

must be depressed a predetermined distance before the oil can escape to the outlet passage and this will insure the presence of a considerable body of oil between the sight 5 glass and the top face of the plunger so that the oil will be easily discernible even though a very light grade of oil is used.

The washer 10 is used merely for the purpose of affording a cushion for the sight 10 glass so that the latter will not become broken.

Referring to Fig. 3 I have shown the plunger formed with an oil passage 15 one end of which opens in the top face of the 15 plunger while the other end opens at the side of the plunger, while a short by-pass 16 leads from the outlet passage 15 into the wall of the recess 6 at a predetermined distance below the oil passage 15 when the 20 plunger is in its normal or projected position, so that it will be clear that no oil can pass into the outlet passage until the lower end of the passage 15 has passed beyond the by-pass 16, thus likewise insuring the presence of a considerable body of oil between 25 the top face of the plunger and the sight glass.

While I have shown the outer face of the plunger 7 normally in contact with the sight 30 glass, this is not at all necessary since such face may be normally spaced from the sight glass for it is impossible for the oil to be delivered into the outlet passage until the plunger has been depressed sufficiently to expose the outlet by-pass.

The incoming end of the outlet by-pass may be located at any predetermined distance below the normal position of the top 40 face of the plunger, according to the nature of the oil utilized, but in all instances the body of oil between the plunger and the sight glass will be sufficient to instantly determine whether or not the forced feed of oil is being properly effected.

45 Having thus described my invention what I claim as new and desire to secure by Letters Patent is:—

1. A sight feed for force feed lubricators, comprising a casing having inlet and outlet 50 communications with the oil supply and

the parts to be lubricated, a sight glass, a resilient plunger normally projected against the glass, and a by-pass leading to the outlet from a point below the relaxed outer face of said plunger and normally closed by the 55 side of the latter.

2. A sight feed for a force feed lubricator, comprising a casing having an outlet and an inlet which respectively communicate with the oil supply and the parts to be lubricated 60 and are capable of communication with each other, a recess in the casing, a seat in the casing surrounding the mouth of the recess, an inlet by-pass terminating flush with said seat, a sight glass confined against said seat 65 over said recess and normally closing said by-pass, a resiliently acting plunger which is normally projected into close contact with the sight glass, and an outlet by-pass which opens into said recess at a point below the 70 bottom face of the sight glass.

3. A sight feed for force feed lubricators, comprising a casing having inlet and outlet communications respectively with the oil supply and the parts to be lubricated, a sight 75 glass, and a resilient plunger normally projected toward the glass, the parts being so constructed and arranged that the oil supply to the outlet will be cut off until the plunger has been depressed by the oil pressure to a predetermined degree.

4. A sight feed for force feed lubricators, comprising a casing having inlet and outlet communications with the oil supply and the parts to be lubricated, a sight glass, a 80 resiliently acting plunger in the casing immediately below said glass, an inlet by-pass leading to a point below said glass whereby oil under pressure will be forced between said glass and plunger to depress the latter, and an outlet by-pass below the top face of the plunger in its relaxed position and always normally closed by the side of the plunger, whereby the outlet for the oil will be open only when the oil pressure shall 85 have forced the top of the plunger beyond 90 said outlet by-pass.

In testimony whereof I affix my signature.

BERNARD H. SKELLY.
